UNITED STATES PATENT OFFICE.

ADDISON B. TINSLEY, OF ANSTED, WEST VIRGINIA.

COMBINED MOLD AND SHIPPING-BOX.

1,205,413.

Specification of Letters Patent. Patented Nov. 21, 1916.

Application filed November 6, 1914. Serial No. 870,642.

To all whom it may concern:

Be it known that I, ADDISON B. TINSLEY, a citizen of the United States, residing at Ansted, in the county of Fayette and State of West Virginia, have invented a new and useful Combined Mold and Shipping-Box, of which the following is a specification.

This invention relates to a combined mold and shipping box especially designed for use in connection with butter.

It has been the practice heretofore to press butter in molds and to subsequently remove the cakes, wrap them and then ship them to the consumers. This has been objectionable because of the handling necessary and because of the further fact that it is a difficult matter to keep dust and dirt from getting under the covering of the butter.

One of the objects of the present invention is to provide a simple and durable box or container in which the butter is to be placed by the manufacturer, the said box or container constituting a mold in which the butter is shipped to the consumer so that, when the butter is to be used it can be removed from the box or mold in a perfectly sanitary condition and with an attractive configuration.

A further object is to provide a box or mold of this type from which the butter can be removed readily without being marred in appearance.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings, Figure 1 is a section through the device showing the paper lining in position to receive the butter prior to sealing. Fig. 2 is a section through the device with the butter sealed therein ready for shipment. Fig. 3 is a side elevation of the sealed mold and shipping box. Fig. 4 is a section on line A—B Fig. 3. Fig. 5 is an enlarged horizontal section through one of the clips or fastening devices used for

holding together the opposed edges of the wall of the box. Fig. 6 is an enlarged section on line C—D Fig. 3. Fig. 7 is a view similar to Fig. 6, but showing a slightly modified structure.

Referring to the figures in which similar reference numerals designate corresponding parts throughout the several views, 1 designates the body of the box or mold, the same being preferably frusto conical. This body can be made continuous or unbroken throughout its circumference or, if preferred, and as shown particularly in Figs. 3 and 4, the said body can be made of a sheet of metal or other like material the opposed edges of which abut as shown at 2. These edges may be held together in any suitable manner as by providing one or more clips such as shown in detail in Figs. 3 and 5. Each clip or fastener includes a loop 3 of spring wire and which is substantially U-shaped, this loop being adapted to engage a beveled lug 4 soldered or otherwise secured to or formed on the body. The parts are so proportioned that when the edges of the body are brought together, each lug 4 will be automatically engaged by its loop 3 and the edges of the body thus held together as shown in Fig. 3.

The upper and lower ends of the body are adapted to be engaged by closures 5 and 6 respectively. These closures are preferably in the form of screw caps and threads may be formed upon the body of the box or mold for engagement by the caps. These threads can be produced by wrapping a wire 7 about the body and soldering it thereto, as shown in Fig. 6, or by soldering or otherwise securing a threaded collar 8 to the body as shown in Fig. 7. In either case, the threads are cut off flush with the edges 2 of the body but are adapted to match or register when said edges are brought together.

An interior shoulder 9 is arranged within the body close to the bottom thereof and can be formed by pressing a bead into the body as shown or by soldering a rib upon the inner surface of the body. The shoulder thus provided is designed to support a die disk or plate 10 which is of a diameter equal to the internal diameter of the body at the shoulder. This plate or disk is so shaped as to produce any desired configuration upon the butter when placed within the box or mold. It is to be understood that instead of mounting the die plate or disk detach-

ably on the shoulder, it can be secured to the body of the container at one or more points. By making the body of the container of metal it will have a certain amount of inherent resiliency so that, when the loops 3 are disengaged from the lugs 4 the body will automatically spring open away from the molded object contained therein. If preferred, however, instead of forming the body of a single strip held together at its free edges by fastening means such as described, it can be made of two opposed sections connected by spring hinges. This structure is so obvious that it is not deemed necessary to illustrate the same in detail.

In using the mold or container herein described, the same is set up by placing the loops 3 in engagement with the lugs 4, inserting the die plate or disk so that it will bear on the supporting shoulder, and screwing the bottom cap 6 into position. A bag preferably formed of paper and which has been illustrated at 11, is then inserted into the container, this bag being of such a size and shape as to fit snugly into the container although projecting a considerable distance above it. The butter is then placed in the bag and packed into the mold or container, the pressure on the butter serving to press the papers into any depressions contained in the die plate or disk so that the butter in the bag will be properly shaped. After the container has been filled in this manner, the projecting portions of the bag are folded together onto the butter, as shown at 12 in Fig. 2. A disk 13 is then placed upon the folded portion of the bag and upon the upper edge of the wall of the container, after which the top cap 5 is fastened in position. The cap binds the disk 13 against the upper edge of the wall of the container so that said disk thus acts as a gasket to seal the container. With the butter thus packed and sealed, the container can be placed in a suitable receptacle and shipped with one or more additional containers to the consumer or distributor. It is designed to make these containers of various sizes, for example, making one size to hold one-quarter pound.

another size to hold one-half pound, another 50 size to hold one pound, etc. In shipping the containers a number of them will be placed in a crate in somewhat the same manner as eggs are shipped. When the butter is purchased, it will be in a perfectly sanitary 55 condition by reason of the fact that it has not been handled since leaving the factory and it has not been possible for dirt or moisture to come into contact therewith. Furthermore when the butter is removed it will 60 present an attractive appearance by reason of the fact that the container in which it has been shipped constitutes a mold.

What is claimed is:—

1. A shipping container for butter and the like, including a frusto-conical body formed in one piece and having detachably connected abutting ends, said body having an inwardly extending annular bead, a die plate resting at its margin upon the bead, a closure detachably engaging the lower end of the body and constituting a support for the die plate, coöperating means upon the abutting end portions of the body for detachably fastening said end portions together, and a 75 closure detachably engaging the upper end portion of the body.

2. A shipping container for butter and the like including a one piece split body having its upper and lower end portions screw 80 threaded and having an inwardly extending annular bead adjacent the lower threaded portion, a die plate removably mounted upon said bead, closures detachably engaging the upper and lower threaded end portions of the body, the lower closure constituting a support for the die plate, lugs outstanding from the body at one side of the split 85 therein, and spring loops extending from the body at the other side of the split 90 and detachably engaging the lugs.

In testimony that I claim the foregoing as my own, I have hereto affixed my signature in the presence of two witnesses.

ADDISON B. TINSLEY.
